UNITED STATES PATENT OFFICE

WILLIAM C. HOLBROOK, OF DAYTON, OHIO, ASSIGNOR TO FRIGIDAIRE CORPORATION, OF DAYTON, OHIO, A CORPORATION OF DELAWARE

REFRIGERATING APPARATUS

Application filed January 31, 1928. Serial No. 250,809.

The present invention relates to improvements in the construction of cabinets for refrigerating apparatus.

It is an object of the invention to provide an improved cabinet wall structure which will permit the passage therethrough of pipes without causing entry of heated air or odors into the refrigerated interior of the cabinet.

10 This effect is secured by providing an improved form of sealed opening for the walls of such a cabinet through which the pipes may pass.

It is a further object of the invention to provide a cabinet wall construction which will facilitate the installation and removal of the refrigerating element from the cabinet and its connection and disconnection with the refrigerant circulating machinery.

20 Further objects and advantages of the present invention will be apparent from the following description, reference being had to the accompanying drawings, wherein a preferred form of the present invention is clearly shown.

In the drawings:

Fig. 1 shows a section through the improved wall seal of the invention; and

25 Fig. 2 illustrates a refrigerator cabinet provided with the improved seal of the invention.

In mechanically refrigerated cabinets in which a refrigerating element is supplied with refrigerating medium by a compressor unit or the like disposed either in another part of the cabinet or at a point remote therefrom it is customary in order to facilitate the installation and removal of the element to run the connecting piping through a wall of the cabinet, preferably the rear wall.

30 In extending the piping to the exterior of the cabinet it is desirable to make as tight a seal as possible in the wall so that warm air may be prevented from entering the refrigerated portion of the cabinet. Hitherto difficulty has also been encountered by the entry of odors into the food compartment and the absorption of such odors by the food. These odors originate from the cork or other heat insulation used in the walls. While

normally odorless the heat insulation may absorb moisture from the air and from the cooling chamber if cut through to permit the extension of the piping and gradually to impart its absorbed odor to the interior of the 55 refrigerator.

These difficulties are particularly encountered when the seal is applied in the field by the installation man or repair man.

By the present invention these difficulties 60 are obviated by providing a seal which is applied during the manufacture of the cabinet and which will effectively seal the interior of the cabinet from the insulation within the walls at the point where the pipes of the system extend through a wall of the cabinet.

Referring in detail to the drawings the improved seal of the invention is shown applied to a mechanically refrigerated cabinet. The cabinet comprises walls composed of a framework 10, outside lining 11 and inside lining 12. The space between the two linings is filled with a suitable heat insulating material such as corkboard or the like, indicated by 13, which is tightly cemented to the linings. The cabinet is equipped with the usual doors 14, 15, giving access to the interior from the front. It is likewise shown divided into a plurality of compartments. One compartment 16 serves as the refrigerating compartment 70 while another 17^a may serve to house the compressor unit. 75

The upper compartment 16 may contain the refrigerating element. The latter is shown by way of illustration as comprising 80 a header 17 carried by the inside top of the cabinet as by brackets 18. A plurality of dependent loops of pipe 19 are connected to the header and serve to form a freezing space arranged to enclose sleeves 20 containing trays 21 for holding substances to be frozen. The refrigerant is supplied to the header by means of a pipe 22 connected with a compressor unit, not shown. It is withdrawn by means of another pipe 23 likewise 85 connected with the compressor.

These pipes, as well as any other pipes used for controlling the operation of the refrigerating element, pass through a wall of the cabinet, preferably the rear wall as 100

shown in Fig. 2. Such pipes may be provided with couplings and flares, and a relatively large opening is required to permit their insertion into the cabinet. The opening through which they pass is closed by means of the improved seal of the invention.

Referring in detail to the construction of the seal shown in Fig. 1, it will be observed that the cabinet wall is provided with a tubular opening extending through from the interior of the cabinet to the exterior.

The opening preferably slants downwardly, although this is to be considered a matter of convenience and not a limitation of the invention, for example the opening may slant in other directions, as when the pipes are run to a compressor which is placed elsewhere than below the cooling compartment. The slanting of the opening saves space by allowing the gradual bends in the pipes to be disposed mainly within the thickness of the wall. The inside lining 12 of the wall is cut out to provide an opening of lesser diameter than that cut out of the rear lining 11. The insulating material 13 is preferably cut away to the same extent as the diameter to the opening of the rear lining.

A tube 27 of heat insulating material, such as fibre or the like, is placed in the hole in the insulation 13 of the wall and is preferably cemented to the insulating material in the same manner as the insulation is cemented to the lining, suitable heat-plastic cement preferably of an asphaltic or tarry nature such as hydrolene being used. The operation being performed by coating the inside of the cavity in the insulating material with the compound mentioned which latter is also preferably applied to the fibre tube 27 as by painting it thereon or immersing the tube in the heated and melted compound. The tube 27 is then pushed into place between the two linings, the insertion of the tube being effected from the rear of the wall so that the overhanging flange members 29 and 30 of the front lining 12 act as a retaining flange or stop for assisting in positioning the tube and preventing its protrusion into the interior of the cabinet. The heavy line 31 indicates the layer of sealing compound or hydrolene, which not only waterproofs the cavity but also cements the tube in place, thus securing a good connection between the insulation and the tube.

The operations above described are performed in the factory and by this method the insulation or corkboard is thoroughly sealed off from the exterior and interior of the cabinet.

When the refrigerating element is to be installed in the cabinet which is usually effected in the field a grommet or bushing 24 of flexible material, such as rubber is passed over the piping so as to embrace it with a snug fit. This grommet is preferably provided with a

groove 32 and projecting bulbous portions 25 and 26 so that it may readily be snapped over the edges of the hole in the lining 12 and gripped by the lining. It may be split or even built in interfitting sections to facilitate insertion of the tubes.

For the purpose of sealing the cavity within the fibre tube 27 a packing of fibrous heat insulating material such as kapok, indicated by 28, is forced into the space within the tube 27.

By means of the arrangement described a yielding nonconducting seal is effected which not only effectively seals the food containing interior of the cabinet against ingress of heated air and odors, but which likewise protects the insulation 13 from absorption of moisture. While virtually permanent it is nevertheless sufficiently yieldable to withstand vibration due to operation of the compressor and at the same time it may readily be dismantled without damage, if the element is to be removed from the cabinet while the installation may readily be effected in the field by the serviceman.

While the form of embodiment of the invention as herein disclosed, constitutes a preferred form, it is to be understood that other forms might be adopted, all coming within the scope of the claims which follow.

What is claimed is as follows:

1. A refrigerator cabinet including a thick insulating wall, a lining for the wall, said wall and lining having a passageway, said passageway in the insulated wall having its end in register with the opening in the lining and having its axis obliquely disposed with reference to the lining.

2. A refrigerating cabinet including a thick insulated wall, a lining for the wall provided with an opening, said insulating wall having a passageway of larger size than said opening with its end in register with said opening and having its axis obliquely disposed with reference to the lining, an insulating tube in said passageway abutting said lining and sealed to said insulating wall, insulating means carried by said lining for centering and sealing piping in said opening and for sealing said opening, said piping having a bend disposed within the wall between said opening and the outside of the wall, and insulation within said tube.

In testimony whereof I hereto affix my signature.

WILLIAM C. HOLEROCK.
